UNITED STATES PATENT OFFICE.

JAY V. ANDREWS, OF CYRIL, OKLAHOMA.

KNEE-PAD.

1,087,863.

Specification of Letters Patent. Patented Feb. 17, 1914.

Application filed April 12, 1913. Serial No. 760,694.

To all whom it may concern:

Be it known that I, JAY V. ANDREWS, a citizen of the United States, residing at Cyril, in the county of Caddo and State of Oklahoma, have invented new and useful Improvements in Knee-Pads, of which the following is a specification.

This invention relates to cushioned knee pads for the use of cotton and berry pickers and others compelled to kneel to work in contact with the ground or floor, the object of the invention being to provide a simple, convenient, easily applied and removed construction of cushioned pad adapted to afford the desired cushioning action and to maintain the knee out of contact with the floor or ground, and which in addition is cool and comfortable to the wearer and may be employed without inhibiting the free circulation of the blood.

The invention consists of the features of construction, combination and arrangement of parts hereinafter fully described and claimed, reference being had to the accompanying drawings, in which:

Figure 1 is a perspective view showing the application of the invention. Fig. 2 is a similar view of the device removed. Fig. 3 is a vertical longitudinal section through the device. Figs. 4 and 5 are vertical transverse sections on the lines 4-4 and 5-5 of Fig. 3.

In carrying my invention into practice, I provide a resilient or spring frame preferably formed of spring wire, and, as shown, of a single piece of spring wire bent into the desired shape. In the illustrated embodiment, the frame consists of upper and lower U-shaped portions 1 and 2, the upper U-shaped portion comprising a pair of parallel side arms 3 and 4 connected at their forward ends by a curved return portion 5, while the lower frame portion 2 comprises a pair of parallel side arms 6 and 7 having inwardly curved forward ends 8 extending on the same arc of curvature as the part 5 of the upper frame portion. The portions 8 constitute the terminals of the length of wire of which the frame as a whole is formed and are welded or otherwise suitably united, as indicated at 8a.

The rear ends of the respective sets of arms 3 and 6 and 4 and 7 are connected by bends or uprights 9 and 10, formed by the intermediate portions of the wire, whereby

the rear end of the upper frame section 1 is integrally connected by spring portions to the lower frame section 2 so as to have yielding movement in a vertical plane. The arms 6 and 7 are connected adjacent to their rear ends by a cross piece or brace 11 which holds the frame sections from spreading laterally, while the forward ends of the respective pairs of arms 3 and 6 and 4 and 7 are connected by uprights 12 welded to the arms 6 and 7 and slideable through eyes 12a on the arms 3 and 4. Coiled springs 13 surround said uprights 12 between the eyes 12a and tensioning nuts 13a at the lower ends of the uprights, which are provided at their upper ends with retaining nuts 8b. These springs restrict the downward cushioning motion of the upper frame section and their yielding resistance may be regulated by adjusting the tensioning nuts 13b.

Suitably fastened to and extending between the arms 3 and 4 of the upper frame section 1 is a pad or apron 14, which is preferably made of canvas or other suitable material and which is designed to bear against the leg and knee of the wearer. This pad is provided at its upper or forward end with a flap 15 adapted to extend over the knee cap and to enable the device to be properly applied in position without constricting the knee motion of the leg. For the purpose of securing the device in position, straps 16 and 17 are arranged at or near the forward ends of the arms 3 and 4 to embrace the leg immediately below the knee joint, one of which straps is provided with a perforated end adapted to engage a buckle upon the other strap. The flap 15 of the apron is provided with similar straps 18 and 19 adapted to encircle the leg above the knee joint and to be similarly secured together, while a third set of straps 20 and 21 are provided and connected with the bends or uprights 9 and 10 to be secured about the leg below the straps 16 and 17, whereby the device may be firmly fastened in place without interfering with the knee motion of the wearer or inhibiting the free circulation of the blood. Any other suitable means for fastening the device upon the person of the wearer may, however, be employed.

The device is applied in position as described and illustrated in Fig. 1, and under the pressure and weight of the knee upon 110

the pad 14 the latter sags and tends to force the frame section 1 downwardly against the resistance of the spring uprights 10 and cushioning springs 13 and to the 5 limit allowed by the said cushioning springs 13; and to a greater or less extent, dependent upon the applied pressure. When the pressure is removed or decreased, by the action of the springs the parts return to 10 normal position, and this cushioning motion is established as the wearer shifts his position upon the ground or floor, thus maintaining a constant yielding spring or cushioning action whereby the knee of the 15 wearer is easily and comfortably supported.

It will be seen from the foregoing description that the invention provides a device of the character set forth which is not only simple of construction, and therefore capable of being inexpensively manufactured, but which maintains the knee of the wearer out of contact with the floor or ground and cushions the weight thereof, thus preventing the 20 bruises and injuries to which workers 25 of the character described are customarily subjected.

A valuable and important feature of the device resides in the fact that the device is light in weight so that it may be worn 30 throughout a working day without physical effort, and that the construction described allows the wearer to walk erect without difficulty.

I claim:—

1. A knee pad comprising superposed U-shaped frame portions integrally connected at one end and having cushioning connections at the opposite end, a flexible apron extending between and secured to the arms of the upper frame portion, said apron having an upwardly extending integral extension, and fastening members upon the frame and extension of the apron for securing the pad to the leg of the wearer. 35

2. A knee pad comprising an open resilient frame formed of spring wire and consisting of an upper U-shaped portion and a lower U-shaped portion, said lower U-shaped portion having its arms connected at their rear ends by yielding uprights with the rear 40 arms of the upright portion, a brace connecting the arms of the lower frame portion, uprights slidably connecting the forward ends of the companion arms of the upper and lower frame portions, cushioning 45 springs associated with said uprights, a flexible apron secured to the arms of the upper frame portion, and means for securing the device to the leg of the wearer. 50

In testimony whereof I affix my signature in presence of two witnesses. 60
